GOVERNOR FOR RECIPROCATING ENGINES

Adalberto Garelli, Milan, Italy

Application March 10, 1933, Serial No. 660,303
In Italy March 25, 1932

7 Claims. (Cl. 264—15)

The invention relates to reciprocating engines provided with centrifugal governors mounted on the crank shaft and has for its object an arrangement of the parts of the governor which, 5 while effecting the normal operation of a centrifugal governor, avoid any increase in the size, and in certain cases also the weight of the crank shaft and consequently the weight of the engine.

According to the invention the centrifugal mass or each of the centrifugal masses is pivoted in a recess provided in a groove or notch of a radial extension of the shaft lying in the plane of one arm of the crank (crank disc or counterweight), the said mass comprising an arm extending 15 toward the axis for acting on an element axially movable relatively to the crank shaft and connected to the member which the governor should control and which is subjected to the action of an antagonistic spring.

On the annexed drawings two embodiments 20 of the present invention are illustrated by way of example and

Figure 1 is a fragmentary section of the end portion of the crank case of a reciprocating engine provided with a governor according to the 25 present invention;

Figure 2 is a section on line 2—2 of Fig. 1;

Figure 3 is a similar section of a construction 30 of a governor comprising symmetrical centrifugal masses and

Figure 4 is the section on line 4—4 of Figure 3.

In the embodiment of Figures 1 and 2 the counterweight 1 of the engine crank shaft 2 mounted to rotate in the engine crank case 3 is provided with a recess 5 located along the 35 diameter passing through the crank pin 4, and a centrifugal mass 7 is eccentrically pivoted within said recess by means of a pivot pin 6.

Said mass 7 has an extending arm 8 which 40 projects towards the axis of shaft 2 and a stem 13 is mounted to move endwise within an axial hole 9 of said shaft, said stem being actuated by arm 8 by the intermediate of roller 11, disk 10 and ball thrust bearing 12.

45 A lever 15 fulcrumed in a fork 16 fastened on the crank case 3 receives by the intermediate of its roller 17 the thrust of stem 13 whose end extends outwardly from the crank case through a bored plug 14, and imparts said thrust, by means 50 of bar 18, to a member controlled by the governor, say to the throttle of the engine carburetor, not shown. As shown in Fig. 1 of the drawings, a coil spring 19 is positioned between the lever 15 and the casing of the engine which 55 serves to return the parts of the governor to

their normal position and to counteract the centrifugal mass of the governor. This structure is similar to that disclosed in the U. S. patent to Parsons, No. 1,454,402.

Owing to the described arrangement the governor is entirely enclosed within the crank case and the centrifugal mass 7 cooperates to provide a balancing counterweight for the crank shaft while the several parts are perfectly lubricated by lubricant contained within the crank case. 5

10 By the described and illustrated arrangement the mass is pivoted adjacent the periphery of the crank arm or counterweight and acts on the endwise movable member 10 with a comparatively large leverage.

15 Thus a sufficiently long stroke of the said member 10 and of its cooperating stem 13 may be obtained even in respect of very restricted oscillations of said mass, the displacements of the mass above referred to being thus unable to materially affect the balance of the crank shaft.

20 Figures 3 and 4 illustrate a similar arrangement comprising two symmetrical masses 7, 7' pivoted at eccentric points thereof within recesses 5, 5' of the crank arm by means of pivot pins 6, 6'; 25 arms 8, 8' control by the cooperation of the described means the endwise movable member 10 which in turn actuates the stem 13 acting on the outer lever 15; in this construction the masses 7, 7' lie in a plane at right angles to the 30 radius on which the crank pin 4 is located.

25 In this case advantages similar to above described ones are secured, with the exception that the centrifugal masses do not cooperate to provide the balancing counterweight which therefore is 35 not longer subject to any alteration whatsoever due to the oscillation of the governor masses.

I claim as my invention:

1. In a reciprocating engine, an engine control member, a crank case, a crank shaft having a 40 crank arm and mounted to rotate in said case, said crank shaft comprising a part extending radially from the shaft in the plane of the crank arm adjacent a wall of the case and having at least one recess extending in radial direction, a mass 45 eccentrically pivoted in each recess about an axis perpendicular to the axis of said crank shaft and adjacent the periphery of the radially extending part of the shaft, each mass having an arm directed toward the axis of said shaft, said 50 crank shaft having an axial bore through its portion on the side of said radially extending part, means operative through said axial bore for transmitting motion from said arm of the mass to the control member, and elastic means opposing the 55

movement of said mass under the action of centrifugal force.

5. In a reciprocating engine, an engine control member, a crank case, a crank shaft having a crank arm and mounted to rotate in said case, said crank shaft comprising a part extending radially from the shaft in the plane of the crank arm adjacent a wall of the case and having at least one recess extending in radial direction, a 10 mass eccentrically pivoted in each recess about an axis perpendicular to the axis of said crank shaft and adjacent the periphery of the radially extending part of the shaft and the side of said part remote from said wall, each mass having an 15 arm directed toward the axis of said shaft, said crank shaft having an axial bore therethrough, means operative through said axial bore for transmitting motion from said arm of the mass to the control member, and elastic means opposing the 20 movement of said mass under the action of centrifugal force.

3. In a reciprocating engine, an engine control member, a crank case, a crank shaft having a crank arm and mounted to rotate in said case, 25 said crank shaft comprising a part extending radially from the shaft in the plane of the crank arm adjacent a wall of the case and having at least one recess extending in radial direction, a mass eccentrically pivoted in each recess about an 30 axis perpendicular to the axis of said crank shaft and adjacent the periphery of the radially extending part of the shaft and the side of said part remote from said wall, each mass having its center of gravity near the periphery of the radial extension of the shaft and having an arm directed toward the axis of said shaft, said crank shaft having an axial bore therethrough, means 35 operative through said axial bore for transmitting motion from said arm of the mass to the control member, and elastic means opposing the movement of said mass under the action of centrifugal force.

4. In a reciprocating engine, an engine control member, a crank case, a crank shaft having a 45 crank arm and mounted to rotate in said case, said crank shaft comprising a part extending radially from the shaft in the plane of the crank arm adjacent a wall of the case and having at least one recess extending in radial direction, a mass eccentrically pivoted in each recess about an axis 50 perpendicular to the axis of said crank shaft and adjacent the periphery of the radially extending part of the shaft, the distance between the center of gravity of the centrifugal mass and its pivot being substantially less than the distance between the axis of the pivot and the axis of the 55 crank shaft, each mass having an arm directed toward the axis of said shaft, said crank shaft having an axial bore through its portion on the

side of said radially extending part, means operative through said axial bore for transmitting motion from said arm of the mass to the control member, and elastic means opposing the movement of said mass under the action of centrifugal force.

5. In a reciprocating engine, an engine control member, a crank case, a crank shaft mounted to rotate in said case and comprising a counterweight having a recess extending in radial direction, a mass eccentrically pivoted in said recess about an axis perpendicular to the axis of said crank shaft and adjacent the periphery of the counterweight, said mass having an arm directed toward the axis of said shaft, said crank 15 shaft having an axial bore therethrough, means operative through said axial bore for transmitting motion from said arm of the mass to the control member, and elastic means opposing the movement of said mass under the action of centrifugal force.

6. In a reciprocating engine, an engine control member, a crank case, a crank shaft having a crank arm and mounted to rotate in said case, 25 said crank shaft comprising a part extending radially from the shaft in the plane of the crank arm and having two opposed recesses extending in radial direction, two masses each eccentrically pivoted in one of said recesses about an axis perpendicular to the axis of said crank shaft and 30 adjacent the periphery of the radially extending part of the shaft, each mass having an arm directed toward the axis of said shaft, said crank shaft having an axial bore therethrough, means 35 operative through said axial bore for transmitting motion from said arm of the mass to the control member, and elastic means opposing the movement of said mass under the action of centrifugal force.

7. In a reciprocating engine, an engine control member, a crank case, a crank shaft having a crank arm and mounted to rotate in said case, 45 said crank shaft comprising a part extending radially from the shaft in the plane of the crank arm adjacent a wall of the case and having two opposed recesses extending in radial direction, two masses each eccentrically pivoted in one of said recesses about an axis perpendicular to the axis of said crank shaft and adjacent the periphery of the radially extending part of the shaft and the side of said part remote from said wall, each mass having an arm directed toward the axis of said shaft, said crank shaft having an axial bore therethrough, means operative 50 through said axial bore for transmitting motion from said arm of the mass to the control member, and elastic means opposing the movement of said mass under the action of centrifugal force.

ADALBERTO GARELLI.
